UNITED STATES PATENT OFFICE

CHARLES SHULMAN, OF NEW YORK, N. Y., ASSIGNOR TO APT NOVELTY COMPANY, INC.,
OF NEW YORK, N. Y.

DESIGN FOR A LIGHTING FIXTURE OR ARTICLE OF SIMILAR NATURE

Application filed October 26, 1931. Serial No. 41,532. Term of patent 3½ years.

To all whom it may concern:

Be it known that I, CHARLES SHULMAN, a citizen of the United States, residing in New York city, in the county of New York and State of New York, have invented a new, original, and ornamental Design for a Lighting Fixture or Article of Similar Nature, of which the following is a specification, reference being had to the accompanying drawings, forming a part thereof.

Fig. 1 is a front elevational view of a lighting fixture showing my new design. The

portions shown in dotted lines are mere repeats of those shown in full outline.

Fig. 2 is a bottom plan view thereof. The portions shown in dotted lines are mere repeats of those shown in full outline.

I claim:

The ornamental design for a lighting fixture, or article of similar nature, as shown and described.

In testimony whereof I affix my signature.

CHARLES SHULMAN.
